UNITED STATES PATENT OFFICE.

JOSEPH BLOCKLEY BEADMAN, OF KEIGHLEY, AND HARRY JOHNSON MACKLIN, OF ULVERSTON, ENGLAND.

JOURNAL-BOX.

1,130,876.

Specification of Letters Patent.

Patented Mar. 9, 1915.

Application filed June 12, 1914. Serial No. 844,651.

To all whom it may concern:

Be it known that we, JOSEPH BLOCKLEY BEADMAN and HARRY JOHNSON MACKLIN, residing, respectively, at 2 West View Terrace, Keighley, in the county of York, England, and 49 Lightburn road, Ulverston, in the county of Lancaster, England, have invented new and useful Improvements in Journal-Boxes, of which the following is a specification.

This invention relates to improvements in journal boxes, more particularly to the type used on railway rolling stock and the like vehicles, and wherein side chambers are provided for the reception of the lubricant in a liquid form. In this type of journal box the lubricant is usually raised by a pad placed beneath and in contact with the journal whereby the lubricant is conveyed to the axle. Also, in this type of journal box provision is made for the reception of the surplus oil when the vehicle is in a tilted position and for siphoning out any water that may have entered the axle box.

Heretofore great difficulty has been experienced in the efficient lubrication of the journal owing to the difficulty of separating and removing collected water from the oil. The water being heavier in gravity sinks to the bottom of the oil chamber and raises the level of the oil higher than some portion of the back of the axle box, thereby allowing the oil to run out and be lost. In axle boxes provided with a separate chamber at the bottom difficulty has been experienced in preventing the outlet for the water to escape becoming clogged with dirt, and thus when the vehicle is tilted the water has become again mixed with the oil.

The object of this invention is to construct a railway or other vehicle axle box with means for separating the water automatically from the oil and conducting it into a chamber provided with a suitable outlet through which the water can escape, and at the same time providing the separating chamber with partitions that will prevent the water, as far as possible, becoming again mixed with the oil.

The above named object is attained by arranging and constructing the axle box as illustrated in the accompanying drawings, in which—

Figure 1 is a sectional elevation of an axle box with the detachable cover fixed

thereto and with a water separating chamber attached thereto, and with holes communicating with the space in which the shield slides, and also provided with vertical partitions and outlets in such shields; 60 Fig. 2, a section on line A, B, Fig. 1; Fig. 3, a sectional elevation of axle box with a tapering well and a recess formed in the division between the oil chamber and the shield guard slide for the water to pass into 65 the latter and having vertical partitions formed therein; Fig. 4, is a section on the irregular line C, D, Fig. 3; Fig. 5, is an enlarged part sectional elevation of the lower portion of Fig. 1; Fig. 6, is a sectional elevation on line E, F, Fig. 5; Fig. 7, is a part plan of Fig. 5; Fig. 8, a part sectional view on line G, H, Fig. 3.

Like parts in all the views are marked with similar letters of reference.

a is a railway vehicle axle box of ordinary construction made of iron and steel, *b* the bottom of the same, *c* the well or space for the reception of oil, and *d* the bush. The axle box is provided with a lubricating pad 80 mounted upon springs. These last named parts are not shown in the drawings. *e* is the axle of the vehicle. The axle boxes shown at Figs. 1 to 4 are provided with bulging sides *f* to form an internal recess 85 or side chamber for the collection of any oil that will run to the side of the axle box when fixed to an end tilting vehicle. *g* is the shield guide or groove, *h* its cover, and *i* the dust shield which is usually made of 90 wood. All the above parts are of the usual and ordinary construction and will be readily understood without further description.

The water chamber *j* is formed either by 95 fixing to the bottom of the axle box a casting *j'* which is secured in position by means of set screws *k* (Figs. 2 and 6), or the water chamber may be formed in the axle box itself, as shown at Figs. 3 and 4, in which case 100 a tapering groove or channel *n* is formed in the bottom of the axle box, and a communication is formed between the shield guide or groove *g* by means of the hole *o*. In the former case where the water chamber *j* is 105 formed in a separate casting two holes *l* and *m* are in communication with the water chamber; the hole *l* communicating at one end with the oil chamber *c*, and at its opposite end with the water chamber *j*, while the 110

ends of the hole m communicate respectively with the shield guide or groove g and the water chamber. The lower portion of the shield groove g is thus made to form a chamber for receiving the water that is separated from the oil.

In this invention the lower portion of the shield groove is divided into three compartments marked in the drawings at Fig. 6 as 1, 2, and 3. The compartment 2 is narrower in width than compartments 1 and 3, and the holes m and n are arranged respectively to communicate with the compartment 2. The compartment 2 is formed by the vertical partitions p , q which are made knife shaped on their upper edges, or well rounded off. The vertical partitions p and q are carried a certain height in the shield groove g and the water from the oil chamber first passes into the water chamber j by gravity and enters the compartment 2 until the latter becomes full. When the compartment 2 becomes full of water, the water escapes from the compartment 2 through the tapering hole r which, as shown at Figs. 1 to 5 in the drawings, is arranged just below the dust shield i .

In some cases it may be found more preferable to arrange an exit hole in each of the compartments 1 and 3, as shown at Fig. 8 of the drawings, the exit holes r^1 in each case being arranged to taper outward so as to prevent them becoming clogged with dust. In this latter arrangement when the compartment 2 becomes filled with water the vertical partitions p and q form a kind of weir over which the water can overflow into compartments 1 and 3, and by arranging the exit holes r' in each of these compartments to be near their bottom and the water readily flows out on each side thereof.

In some cases it may be found more convenient to place the exit holes r , r^1 in the bottom of the compartments 1 and 3, as shown in dotted lines at r^2 , Fig. 8 instead of at the sides, as shown in full lines in the same view. Or, in other cases instead of employing a hole tapering outward a parallel hole may be employed having an internal screw thread cut thereon into which a short elbow pipe r^3 is inserted, as shown in dotted lines at Fig. 8. The orifice of the outer end of the elbow pipe r^3 may be either parallel or arranged to taper outward.

It will readily be understood that the means for separating the water from the oil is controllable by gravity alone. In the operation the water would collect in the shield groove g through which it passes from the oil chamber c through either hole l or n and will rise in the compartment 2 until it reaches the top of the vertical partition p and q when it would overflow into compartment 1 or 3 or both, and would afterward pass out through the exit hole or holes

r^1 . The pressure of water would clear away any obstruction in the exit holes which are made to taper outward and therefore present very little surface for the dust to lodge thereon.

What we claim is:

1. In an axle box for railway vehicles the combination of a receptacle adapted for the reception of a fluid lubricant having a specific gravity less than that of water and provided with a rear compartment communicating at its bottom with the receptacle, an axle extending into said receptacle, said receptacle having vertical grooves in one side thereof, a shield engaging in said grooves adapted to prevent the free entrance of water into the receptacle, and a pair of vertical partitions extending from the bottom of said rear compartment, said rear compartment having water outlets in the side thereof whereby to admit of the escape of the water by gravity from the compartment.

2. In an axle box the combination of a receptacle adapted to contain a fluid lubricant and having a separating chamber communicating therewith for removing water from the lubricant, said receptacle having an aperture therein leading to the separating chamber, a plurality of partitions arranged in said separating chamber providing a number of compartments therein, said partitions being arranged whereby to provide a central compartment smaller than the remaining compartments, said separating chamber having in one side an outwardly tapering opening communicating with said smaller compartment to admit of the escape of the separated water.

3. In an axle box, the combination of a receptacle adapted for the reception of a fluid lubricant and having a separating chamber communicating therewith, partitions arranged in said separating chamber whereby to provide a number of compartments therein, said receptacle having vertical grooves in one side thereof, a shield mounted in said grooves adapted to prevent the free entrance of water to said receptacle and constituting a partition between the receptacle and the separating chamber, a plurality of partitions arranged in the lower part of said separating chamber provided with knife edges and forming a plurality of compartments in the separating chamber, said separating chamber having an opening through one side thereof communicating with one of the compartments whereby to admit the escape of water overflowing into said compartment.

4. In an axle box for railway vehicles, the combination of a receptacle provided with a compartment for holding a fluid lubricant having a specific gravity less than that of water, an axle extending into said receptacle

cle, said axle box having vertical grooves in one side thereof arranged opposite to each other, a shield engaging in the grooves providing a compartment for the reception of water separated from the lubricant, said axle box having a chamber communicating with the fluid lubricating compartment and with the separated water chamber, and vertical partitions arranged in the lower part 10 of the separating chamber dividing the same into a number of compartments, the central of such compartments being smaller than the remaining ones and being in communication with the fluid lubricant chamber,

said central compartment being adapted to 15 receive the water from said lubricant, the water being adapted to overflow from the central compartment into the other compartments, said separating chamber having in the wall thereof outward flaring holes communicating with the central compartment through which the water is adapted to escape from the axle box.
